UNITED STATES PATENT OFFICE.

BENJAMIN R. CHASE, OF BOSTON, MASSACHUSETTS, ASSIGNOR TO B. F. STURTEVANT COMPANY, OF BOSTON, MASSACHUSETTS, A CORPORATION OF MASSACHUSETTS.

VACUUM-CLEANER.

1,187,416.

Specification of Letters Patent. Patented June 13, 1916.

Application filed May 4, 1910. Serial No. 559,322.

To all whom it may concern:

Be it known that I, BENJAMIN R. CHASE, a citizen of the United States, residing at Allston, Boston, in the county of Suffolk and State of Massachusetts, have invented certain new and useful Improvements in Vacuum-Cleaners; and I do hereby declare the following to be a full, clear, and exact description of the invention, such as will enable others skilled in the art to which it appertains to make and use the same.

The present invention relates to an improvement in vacuum cleaners.

The object of the invention is to produce an improved form of vacuum cleaner which is simple and efficient in construction and easily adapted for the removal of the dirt collected by the machine.

To the above end the invention consists in the vacuum cleaner hereinafter described and particularly defined in the claims.

In the accompanying drawings illustrating the preferred form of the invention, Figure 1 is a sectional elevation; Fig. 2 is a front view; and Figs. 3, 4 and 5 are details of the construction hereinafter referred to.

The illustrated embodiment of the invention is described as follows: The cleaner consists of a motor, fan and dust collecting devices, mounted upon wheels so as to be capable of being rolled around from place to place where it is desired to use the cleaner. The motor is mounted on a portion of the frame 1, and connected by means of the motor shaft 2 with the fan 3, arranged in its casing 4, to which a handle 5 is attached. The fan-casing 4 is provided with ears, in which the rubber tired wheels 6 and 7 are journaled. The fan-opening or eye 8 is covered by a wire screen 9 which affords a considerable area for the support of the dust-bag 10. The dust collecting devices comprise the dust-bag 10 and the dust-can 11 which is cylindrical in form and extends from the fan-casing forward. This dust-can is made of sheet metal. The rear end of the dust can is secured by rivets to the flange 12 projected forwardly from the face of the fan-casing 4, and it is secured by a row of rivets at its forward end to the flange-ring 13 at the front end of the casing. This flange-ring 13 carries ears 14 in which the forward roller 15 is journaled. The front end of the fan-casing is closed by a two-part head. The lower half 16 of the dust-can head is secured to the flange-ring 13 by means of a series of screws, the joint between the plate 16 and the flange-ring 13 being rendered practically tight by use of a felt gasket. The upper part 17 of the dust-can head is hinged at 18, 60 19 to the upper edge of the lower plate 16. This plate 17 comprises a hinged dust-door for the introduction and removal of the dust-bag and it is provided at 20 with an opening for the ingress of the dust-laden air, 65 a pipe 21 being provided to receive the dust-pipe end and to discharge inside of the dust-bag. The door 17 is secured in closed position by means of swing-bolts 22 which are pivoted to ears on the flange-ring 13 and 70 swing through notches in the edge of the door 17 into position to have the wing-nuts screwed up against the outside of the door-edge in order to hold the door closed. The dust-bag is a canvas bag having a mouth-ring 23 inclosed in a hem at its mouth. By reference to Fig. 3, the mouth-ring 23 will be seen to have an L-shaped cross section; it is received within a hem formed in the mouth of the bag. This mouth-ring 23 is 75 formed at its corner in the manner illustrated in Fig. 4 wherein it will be observed that a notch is cut in the flange 24 to permit the bending of the flange and ring proper 80 at right angles to each other. The cross-section of the ring along the portion thereof which extends across the lower part of the doorway is shown in Fig. 3, while the cross-section of the portion of the ring which extends along the upper part of the doorway 85 is indicated in Fig. 4, the flange being wider throughout this portion. The mouth-ring holds the mouth of the bag to the shape of the door and enables the bag to be readily inserted and removed and conveniently 90 turned inside out for the purpose of removing the dust therefrom. After the machine has been in use, the door 17 will be opened by loosening the swing-bolts, then the door will be dropped down, releasing the bag. 100 The bag may then be removed from the machine and the dust contained therein may be emptied out, also the bag may be turned inside out and beaten for the purpose of removing any dust adhering to the canvas. 105 Then the bag is easily put back by thrusting the body of the bag through the door, by placing the mouth of the bag in position to be embraced between the edges of the door 110 and flange-ring 13 and the lip 26. It will

be observed that the outer edge of the door 17 is recessed on its inner side so as to receive the mouth-ring and the edge of the mouth of the bag. This packs the joint between the door and flange and prevents loss by admission of air at this joint. The bag in use spreads itself over a considerable area of the wire screen 9, as shown. The dust-laden air entering the bag deposits its dust 10 in the bag and the air passes on through the canvas into the fan and is discharged through the outlet 27 from the fan.

In operating the improved cleaner the motor driven fan creates a suction through 15 the substantially horizontal exhaust passage or fan opening 8 to draw air through the dust bag 10 which is of greater length and smaller diameter than the inclosing dust can to cause the bag to engage with a 20 protecting screen 9 of greater area than the area of the exhaust opening and extending in front of and separated from the end wall of the dust can around the opening to prevent the dust bag from being drawn against 25 the opening and to afford a free air passage behind the screen for the passage of air to the exhaust opening from the space left between the dust bag and the sides of the dust can. The current of air passes above the lowest 30 portion of the bag which extends downwardly below the exhaust opening and serves to retain the accumulated dust. The current of incoming air is not compelled to pass through the accumulated dust and the 35 dust separated from the air by the walls of the bag does not drop downwardly against the current of air, all of which tends to improve the efficiency of the device. The centrifugal fan is provided with an axially disposed opening located in the vertical wall 40 of the fan casing which also forms the end wall of the dust can.

Various devices for supporting a bag in a cleaner have been proposed, but this form 45 of bag-support especially commends itself to the user, because it is supported in such a position that when the door is opened to remove the bag, the contents of the bag do not spill upon the floor, the bag itself being 50 normally supported in position to hold the dust which has collected therein, so that the user may remove the bag with the dust in it when he desires to empty it. This flows from the fact that the dust-can is provided with a bag-opening located above the bottom of the can. Again, the mouth of the bag being provided with a mouth-ring, it is convenient to handle with its load of dust and convenient for positioning in the 55 machine when it is desired to replace it. Furthermore, the mouth-ring secures a complete closure of the space between the door and the wall against which it closes, thereby acting as a gasket in this capacity, the 60 act of replacement of the dust-bag render-

ing unnecessary any separate attention to a tight-fitting joint. Another advantage arising from the invention is that the dust falls to the bottom of the bag while the air is withdrawn principally from the end and 70 the air is not required to be drawn through the growing deposit of dust. In this way the machine is capable of being run a much longer time without emptying the dust-bag. In this connection it is to be observed that 75 the entering blast of dust-laden air impinges directly upon the end of the bag close to the fan, with the result that the principal part of the air is drawn through this portion of the bag. Of course, the air is not uniformly 80 laden with dust at all times, because the operator presents the nozzle to a dusty place and then to a place where less dust is to be lifted, with the result that in the intervals between the presentation of the nozzle to 85 the dusty places, the air is comparatively free from dust, and such clean air displaces from the end of the bag the dust which has just previously collected there from the dust-laden air which preceded it. Another 90 feature of advantage in the present construction flows from the large bag area which provides ample opportunity for the escape of the air from the bag. This permits the machine to be run for a considerable length of time without such a thick deposit of dust on the inside of the bag as to require emptying the bag. These features of the construction not only commend themselves to the user, by virtue of the advantages which they secure to him, but they also commend themselves to the manufacturer, by reason of the simplicity of the construction of the machine and the facility 95 with which it may be manufactured.

Having thus described the invention, what is claimed is:—

1. A vacuum cleaner, having, in combination, exhaust-mechanism and dust-collecting devices comprising a dust-can having two 110 openings therein on opposite sides and above the bottom for the ingress and egress of the air respectively so that the circulation of the air is across the upper part of the dust-can, a dust-bag having its mouth inclosing the 115 ingress opening and when expanded substantially filling the dust-can and having its closed end hanging down into the lower part of the dust-can below and out of line with the egress and ingress openings, a substantially vertical screen over the mouth of the egress opening against which the side of the bag opposite the ingress opening is held by the suction of the exhaust mechanism, so that the air which passes across the 120 upper part of the dust bag cavity deposits its dust against the side wall of the bag covering the vertical screen, from which the dust drops to the bottom of the bag in which there is no forced circulation of air, whereby 125 130

the dust-filtering part of the bag is automatically kept clean of a thick deposit of dust, substantially as described.

2. A vacuum cleaner, having in combination, a dust can having a substantially horizontal exhaust passage opening at one side, a dust bag in the dust can having a portion extending downwardly below the exhaust opening, and a substantially vertical 10 screen of greater area than the exhaust

opening and located in front of the opening and in front of and separated from the walls of the dust can around the opening to prevent the dust bag from being drawn against 15 the opening, and to afford a greater screen area than the area of the opening.

3. A vacuum cleaner, having in combination, a dust can, a dust bag in the dust can, a centrifugal fan, a fan casing forming the 20 end wall of the dust can, the fan casing having its inlet opening or eye communicating with the interior of the dust can, and a screen of greater area than the fan opening or eye located in front of said opening, and 25 separated from the fan casing so as to prevent the dust bag from being drawn against the fan casing adjacent the eye, and to afford a greater screen area than the area of the eye.

30 4. A vacuum cleaner having, in combination, a dust can having a horizontal exhaust passage opening in one end, a horizontally disposed dust bag having its mouth secured to the opposite end of the dust can and of greater length and smaller diameter than the dust can, and having a portion extending below the exhaust opening, a substantially vertical screen over the mouth

of the exhaust opening of greater area than than the exhaust opening and extending in 40 front of and separated from the end wall of the dust can around the opening so as to prevent the dust bag being drawn against the opening and to afford a free air passage behind the screen to the exhaust opening for the passage of air from the space left between the dust bag and the sides of the dust can.

45 5. A vacuum cleaner having, in combination, exhaust-mechanism and dust-collecting devices comprising a dust-can having two 50 openings therein on opposite sides and above the bottom, for the ingress and egress of the air respectively, so that the circulation of the air is across the upper part of the dust-can, a dust-bag having its mouth inclosing the ingress opening and having its upper part located between and substantially in line with the ingress and egress openings and having its lower part below and out of 55 line with the ingress and egress openings, and a substantially vertical screen over the mouth of the egress opening against which the side of the dust-bag opposite the ingress opening is held by the suction of the exhaust-mechanism, so that the air which passes across the upper part of the dust-bag 60 deposits its dust against the side wall of the bag covering the vertical screen, from which the dust drops to the bottom of the bag in 65 which there is no forced circulation of air.
